UNITED STATES PATENT OFFICE.

FREDERICK E. WRIGHT, OF WASHINGTON, DISTRICT OF COLUMBIA.

EYEPiece-PRISM.

1,370,938.

Specification of Letters Patent.

Patented Mar. 8, 1921.

Application filed June 26, 1919. Serial No. 307,011.

(FILED UNDER THE ACT OF MARCH 3, 1883, 22 STAT. L., 625.)

To all whom it may concern:

Be it known that I, FREDERICK E. WRIGHT, a citizen of the United States, and a resident of Washington, D. C., have invented 5 an Improvement in Eyepiece-Prisms, of which the following is a specification.

The invention described herein may be used by the Government, or any of its officers or employees in prosecution of work 10 for the Government, or by any other person in the United States, without payment of any royalty thereon.

My invention relates to new and useful improvements in the arrangement and type 15 of eye piece prisms used in base line telemeters.

The objects are simplicity of construction, freedom from cemented and also from silvered surfaces, both of which are liable to 20 give trouble in the course of time, the former because of decrease in transparency and of strains and slight shifts which may be introduced by the drying out of the cement, and the latter by the deterioration of the 25 silvered surfaces.

Figure 1 is a top view of my invention giving an erect image.

Fig. 2 is a side view of the same.

Fig. 3 shows the image in the field of view 30 as seen by the observer.

Fig. 4 is a plan view of an arrangement of prisms which produces an inverted image.

Fig. 5 is an elevation of same.

Fig. 6 shows the image in the field of 35 view as seen by an observer.

Figs. 7 and 8 show plan and elevation of eye piece prisms in which the emergent rays are inclined at an angle of thirty degrees to the vertical.

40 Figs. 9 and 10 show a similar arrangement for an inverted image.

Figs. 11 and 12 show prism arrangements for rays emerging at forty-five degrees to the vertical. Fig. 11 gives an erect image 45 while prism 2 of Fig. 12 gives an inverted image.

Fig. 13 is an end view, showing a rhomb shaped prism attached to the upper prism.

Instruments of the type to which this 50 invention is applicable consist usually of a pentagonal prism at each end of a base line of fixed length, which prisms reflect the light rays from the object whose range is being measured, into the tube which houses 55 separate optical systems in each half, con-

sisting principally of the penta prisms above mentioned, the objective lenses, the angle measuring prism, and the coincident or deviating prisms which reflect the light from each end of the telescope into the eye piece. 60

This invention relates particularly to the type of deviating prisms used for the purpose of securing the coincidence of the images. The eye piece prism consists of two prisms 1 and 2, the prism 1 in this case being superimposed upon the prism 2 so that their hypotenuse surfaces 3 and 4 cross as indicated in Fig. 1. The range finder's field of view is divided into two parts by the horizontal line 5, in Fig. 3, formed by the 65 edge 6 of the total reflecting prism surface 7.

Figs. 4 and 5 are prisms of different shape similarly disposed as in Fig. 1 but the lower prism 2 giving three reflections and therefore an inverted image as shown at the top 70 of Fig. 6.

The reflecting surfaces of prism 2, Fig. 2, are of the roof-edge type, including an angle of ninety degrees with each other and 75 their line of intersection including an angle of forty-five degrees with the side surfaces of the prism.

Figs. 7 and 8 show a disposition of prisms similar to Fig. 1, except that the last reflecting surfaces 7 and 8 are at such an angle that the emergent rays are inclined at an 80 angle of thirty degrees to the vertical.

Figs. 9 and 10 are similar to Figs. 7 and 8 except that the reflecting surfaces of prism 90 2 are shaped so as to give three reflections and, therefore, an inverted image.

Figs. 11 and 12 show views of prism arrangements for rays emerging at forty-five degrees to the vertical, Fig. 11 giving an 95 erect image while the prism 2 of Fig. 12 gives an inverted image.

In case it is desired to have the rays from both objectives pass along the axis of the tube, a small rhomb shaped prism 3' is used 100 as in Fig. 13 to raise the line of sight, from the optical system of one side, so that the upper prism will function properly.

The rhomb shaped prism may be secured to the upper prism by cementing it to one 105 of its side surfaces or by placing the two prisms in optical contact. The second method requires a high degree of skill in manufacture but the finished prism has then an advantage of remaining fixed in position 110

and free from strains and slight shifts which may be introduced by the drying out of the cement.

It will be understood that the angle of incidence in each of the cases cited above is greater than the critical angle of the glass thereby giving total reflection and doing away with the necessity of silvered surfaces.

The path of rays of light passing through the prisms of Fig. 1 is as indicated by the rays R and r. The rays R coming from the right hand end of the tube are reflected by surface 3 to surface 7 and thence into the ocular, being reflected perpendicular to the exit surface 9. The rays r coming from the left hand end of the tube are reflected by surface 4 to surface 8 and thence into the ocular being reflected perpendicular to the exit surface 10. The images thus formed are brought into coincidence as shown in Fig. 3.

In Figs. 4 and 5, the rays R are reflected at R' and R² as described under Fig. 1 while the rays r entering the lower prism are reflected by the roof-edge surfaces 11 and 12 to the surface 8 as indicated by r, r² and thence into the ocular, the emergent rays r³ being perpendicular to the exit surface 10.

From the description of the reflections in Figs. 1 to 6, it is believed the operation of the modifications shown in the remaining figures will be clear.

In Figs. 7, 8, 9, 10, 11 and 12, the reflecting surfaces are so arranged that the emergent rays make an angle with the vertical which is less than a right angle.

In Fig. 13 the rhomb shaped prism 3' is attached to the upper prism 1 in order to raise the line of sight of the right hand optical system so that the rays will pass

through the upper prism and be reflected as described above.

The separate optical system in each half of the tube or telescope body, transmits light to a common field eyepiece, so that the partial images of the target may be seen simultaneously. The modifications shown in the other views, Figs. 4 to 13 are for the purpose of securing erect or inverted images and in directing the emergent rays at various angles so that the direction of view for the observer can be obtained which may give a more comfortable observing position.

Having described my invention, what I claim as new and desire to secure by Letters Patent, is:—

1. In a base line telemeter, a deviating prism for each optical system of the telescoping body, one superimposed upon and in optical contact with the other, each prism comprising a plurality of total reflecting surfaces for reflecting the light rays from each optical system into the ocular, the edge of one of the total reflecting surfaces forming a horizontal dividing line in the field of view, the last reflecting surface of each prism being so disposed as to give the emergent rays a predetermined angle with relation to the plane of the measuring triangle.

2. In a base line telemeter in which the light rays from both objectives are along the axis of the tube, two deviating prisms, one superimposed upon the other, a rhomb shaped prism for reflecting the rays from one of the objectives to the deviating prism which is not in alinement, the two last mentioned prisms being placed in optical contact.

FREDERICK E. WRIGHT.
